Lacy & Lacy, Attorneys

UNITED STATES PATENT OFFICE.

ANDREW W. KNITTEL, OF NEW CASTLE, PENNSYLVANIA; MARY KNITTEL ADMINISTRATRIX OF SAID ANDREW W. KNITTEL, DECEASED.

CURTAIN STRETCHER.

Application filed September 25, 1925, Serial No. 58,573. Renewed May 19, 1927.

This invention relates to curtain stretchers and has for its object the provision of a novel construction whereby the stretcher may be expeditiously set up for use and when so set up will be firm and steady. The invention also seeks to provide a novel construction whereby the several parts of the device may be easily folded into compact form and stored in a small space when not in use and when arranged for use will be held against collapse. Other objects will appear incidentally in the course of the following description, and the invention resides in certain novel features which will be particularly pointed out in the appended claim.

In the drawings:

Figure 1 is an elevation of a curtain stretcher embodying my present improvements;

Fig. 2 is an end elevation of the same;

Fig. 3 is an enlarged detail section on the line 3—3 of Fig. 1;

Fig. 4 is a similar view on the line 4—4 of Fig. 1;

Fig. 5 is a similar view on the line 5—5 of Fig. 1, and

Fig. 6 is an enlarged sectional elevation of the joint in the stretcher bars.

In carrying out my present invention, I employ end supporting frames each of which consists of a pair of legs 1 which may be of any preferred dimensions and are adapted to rest at their lower ends upon the ground and converge upwardly, as clearly shown in Fig. 2. The upper extremities of the legs are beveled, as shown at 2, and upon the outer faces of said members at their upper ends are secured hinge plates 3 which project slightly beyond the ends of the respective legs and are constructed with or formed into sleeves or eyes 4 in which is engaged a connecting link or ring 5. By connecting the upper ends of the legs in this manner, they may be easily spread apart to be set up for use, as shown in Figs. 2 and 3, and when they are not in use one leg may be folded about its respective eye or sleeve 4 so as to lie flat against the outer face of the other leg and thus be brought into a very compact form. To prevent spreading of the legs when they are set up for use, I pivotally attach to one leg a rod 6 having its

end formed into a hook 7 adapted to engage through an eye 8 upon the other leg so that the two legs will be firmly held against spreading in an obvious manner.

The bevel 2 at the upper end of each leg is disposed at such an angle that, when the legs are set up for use, as shown in Fig. 3, the two bevels will be parallel and lie in vertical planes. They are thus properly arranged to bear against the opposite sides of a top stretcher bar 9 which has its upper edge given the ogee form shown most clearly in Fig. 3 to define a central longitudinal rib or tongue 10 and grooves or shoulders 11 at the base of the tongue on each side thereof. Upon each shoulder 11 are provided pins 12 which project upwardly therefrom when the device is set up for use and are adapted to receive the upper edges of curtains which are to be stretched. The stretcher bar 9 may be easily inserted upwardly between the legs and will frictionally engage therewith so that they are clamped by and between the legs, but in order to positively prevent dropping of the stretcher bar I provide brace rods 13 which are each pivotally attached at one end to one of the legs and formed at its opposite end with a hook 14 adapted to engage through an eye 15 on the under side of the stretcher bar, as shown in Figs. 1 and 2. The ends of the stretcher bar will in this manner be firmly supported so that dropping of the bar and consequent soiling of the curtains arranged upon the device will be prevented.

The stretcher bar is constructed in two sections which are adapted to align longitudinally when in use, as shown most clearly in Fig. 6, and the meeting ends of the sections are provided in their lower portions with cut-away surfaces 16 which together form a notch to receive the clamping bolt 17, the ends of the sections above the bolt being at right angles to their upper edges so as to squarely abut, as shown at 18 in Fig. 6, and thereby limit the relative movement of the sections in one direction. The respective sections of the stretcher bar are pivotally attached, as at 19, to coupling plates 20 which are disposed at the sides of the sections and bridge the ends thereof. The bolt 17 is inserted through these coupling plates 20 and

is equipped at one end with a wing nut 21 adapted to be turned home against the adjacent coupling link when the bar is arranged for use so that the two sections 5 will be firmly clamped in alinement. Upon reference to Fig. 6, it will be readily noted that the sections may be swung upwardly about their respective pivots 19, as indicated by dotted lines, so that they may assume approximately parallel positions to be stored 10 away in a small space, the nut 21, of course, being loosened sufficiently to permit this movement. When the device is to be used, the meeting ends of the sections are swung 15 together to the position shown in full lines in Fig. 6, the inclined or cut-away surfaces 16 moving past the bolt and the movement being arrested by the upper end surfaces abutting and by the shoulders 22, formed 20 upon the sections, meeting the bolt 17. The legs are constructed with longitudinal slots 23 and through the said slots are inserted bolts 24 whereby brackets 25 may be secured to the legs. The brackets, as shown 25 most clearly in Fig. 4, consist of a metal plate bent to define approximately a right angle having one side bearing against the outer surfaces of the legs and turned laterally to form a toe 26 resting against the leg so that marring or cutting of the leg by the bracket will be avoided. The longer side of the bracket is provided with an opening 30 therethrough to receive the end of the bolt 27 and a wing nut 28 is mounted upon the bolt at the outer side of the bracket to be turned home against the same and secure the parts in operative position. A lower stretcher bar 29 is engaged between the brackets 25 and the respective legs and this stretcher 35 bar is also made in sections connected by coupling links 30, corresponding in all respects to the coupling links 20 previously described and provided in connection with the upper stretcher bar 9. The lower 40 stretcher bar, however, does not have a central longitudinal vertical rib, such as the rib 10, but has its upper corner cut away to provide a recess or groove 31, and curtain engaging and holding pins 32 are mounted in 45 the stretcher bar so as to project outwardly therefrom through the said recess, as clearly shown in Fig. 4. Both stretcher bars, as well as the legs, may have their outer surfaces graduated, as indicated at 33, to denote 50 inches so that the parts may be accurately adjusted to the dimensions of the curtain or curtains which are to be stretched, and it will be readily understood that by shifting the bolts 24 along the slots 23, the lower 55 stretcher bar may be placed at any desired position. It will also be understood that the respective legs may be placed at any desired point between the ends of the stretcher bars and a plurality of eyes 15 may be provided upon the upper stretcher bar so as to

accommodate the various adjustments. After the lower stretcher bar has been placed in position between the respective legs and the brackets 25, the wing nuts 28 are turned home and the bars will then be very firmly secured, resting upon the legs and also being carried to some extent by the bolts 24. 70

I also provide an intermediate leg 34 which corresponds to one of the legs 1 and is provided with a longitudinal slot 35 receiving an additional bolt 24 cooperating with an additional bracket 25 to engage the lower stretcher bar. To the inner or rear side of this intermediate leg 34, at the upper end thereof, I secure a bracket 36 which extends to the beveled face 37 of the leg and is then carried rearwardly and then upwardly, as shown at 38 in Fig. 5, to engage around the upper stretcher bar 9 and aid in supporting the same. The upstanding terminal portion of the bracket 36 is intended to firmly bear against the rear side of the upper stretcher bar, and to maintain such engagement a set bolt 39 is provided to pass through the depending portion of the bracket and through an opening provided therefor in the leg 34, a wing nut 40 being mounted upon the front end of said bolt and adapted to be turned home against the intermediate leg, as will be understood upon reference to Fig. 5. The legs 1 and 34 are each provided with a groove or recess 41 extending along its front face and pins, indicated at 42, are fixed in said grooves to project therefrom in position to engage the end edges of curtains. 90

From the foregoing description, taken in connection with the accompanying drawings, it will be seen that I have provided a very simple structure whereby the curtain frame may be very easily set up for use or knocked down and arranged in compact form when it is not in use and when set up will be very firm and steady. Both sides of the device, when it is set up for use, may be utilized to have curtains applied thereto, and it is obvious that curtains of certain dimensions may be applied to and supported by one side of the frame and that shorter or narrower curtains may be at the same time applied to the opposite side of the frame, the intermediate leg 34 being adjusted to accommodate the shorter or narrower curtains. It will also be understood that the lower 110 stretcher bars may be adjusted independently so that a wide range of adjustment is permissible and the drying and stretching of curtains may be speedily accomplished inasmuch as it is not necessary to have the drying of one set of curtains completed before applying another set of curtains to the device. 115

Having thus described the invention, I claim: 120

A curtain stretcher comprising pairs of 125

legs, hinge plates secured to the outer surfaces of said legs at the upper ends thereof, a link connection between the extremities of said hinge plates whereby the legs may fold 5 one upon the other or be set up in downwardly diverging relation, means cooperating with the legs to prevent spreading there-

of, lower stretcher bars supported by the legs, and an upper stretcher bar disposed between the upper extremities of the legs below the hinge connections thereof and clamped by and between the legs. 10

In testimony whereof I affix my signature.
ANDREW W. KNITTEL. [L.S.]
